FIG. 1

FIG. 2

FIG. 3

FIG. 4

FIG. 5

FIGURE 1 is a side elevational view of a combined arm rest and storage receptacle, showing my new design; FIGURE 2 is a top view thereof; FIGURE 3 is a bottom view thereof; FIGURE 4 is a front elevational view thereof; and FIGURE 5 is a rear elevational view thereof. The design is characterized by a substantially straight rear wall in combination with a contoured front wall forming a forwardly projecting nose piece substantially as shown.

I claim:

The ornamental design for a combined arm rest and storage receptacle, substantially as shown and described.
